BOATING PADDLE

Elmo J. Mouton, Rte. 1, Box 27N,
Beaumont, Tex. 77708

Filed Aug. 6, 1969, Ser. No. 18,565

Term of patent 14 years

Int. Cl. D12—99

U.S. Cl. D71—1

FIG. 1 is a front elevational view of the boating paddle constructed in accordance with my design;

FIG. 2 is a side elevational view of the boating paddle shown in FIG. 1;

FIG. 3 is a top view of the boating paddle shown in FIG. 1; and

FIG. 4 is a bottom view of the boating paddle shown in FIG. 1.

I claim:

The ornamental design for a boating paddle, as shown and described.
